DESIGN FOR A CABINET FOR RADIO-
RECEIVER

Raymond G. F. Loewy, New York, N. Y., assignor
to Colonial Radio Corporation, Buffalo, N. Y., a
corporation of New York

Application June 24, 1933. Serial No. 48,524

Term of patent 14 years

To all whom it may concern:

Be it known that I, RAYMOND G. F. LOEWY, a citizen of France, residing at 55 Central Park West, New York, in the county of New York and State of New York, have invented a new, original, and ornamental Design for a Cabinet for Radio-receiver, of which the following is a specification, reference being had to the accompanying drawing, forming part thereof, in which

The figure is a perspective view of a cabinet for radio receiver according to my invention, the receiver cabinet being in the form of a base carry-

ing a terrestrial globe having a map of the world thereon. While the drawing shows only one side of the cabinet, it will be understood that the side not shown has the same general appearance as that shown, except for the delineation of oceans and continents.

I claim:

The ornamental design for a cabinet for radio-receiver substantially as shown and described.

New York, N. Y., June 16, 1933.

RAYMOND G. F. LOEWY.
